UNITED STATES PATENT OFFICE.

EDWARD T. WILLIAMS, OF CARROLLTON, KENTUCKY.

GRINDING-MILL.

SPECIFICATION forming part of Letters Patent No. 400,533, dated April 2, 1889.

Application filed February 12, 1887. Serial No. 227,408. (No model.)

To all whom it may concern:

Be it known that I, EDWARD T. WILLIAMS, a citizen of the United States, residing at Carrollton, in the county of Carroll and State of Kentucky, have invented a new and useful Improvement in Grinding-Mills, of which the following is a specification.

The invention relates to improvements in grinding-mills; and it consists in the construction and novel combination of parts hereinafter described, and pointed out in the appended claim.

In the drawings, Figure 1 is a plan view of a grinding-mill having the invention attached. Fig. 2 is a perspective view of the adjusting mechanism for the movable roller. Fig. 3 is a detail sectional view on the line $y-y$ of Fig. 1. Fig. 4 is a side view of the rollers and adjusting mechanism. Fig. 5 is a detail transverse section on the line $z-z$ of Fig. 3.

Referring to the drawings by letter, A designates the main casing, having secured to it the bearing-blocks B for the journals of the roller C. This roller has at its ends the cams D, which bear against the anti-friction rollers E. This construction is preferable; but the cams and anti-friction rollers form no part of the invention.

F F designate a pair of longitudinally-moving bearing-blocks, which are to rest upon the upper sides of the inclosing-case A, and are provided on their outer sides with the horizontal arms G, which enter and are guided in keepers H, that are secured to the upper ends of the inclosing-case. From the upper sides of the arms G project studs I. The vertical end walls, h , of the keepers have their opposing sides arranged parallel, as shown in Fig. 1.

K designates a pair of slide blocks or keys, which are each provided with an oblique slot, L, that is open at one end. The said slide blocks or keys are arranged transversely in the keepers, and the studs I enter the oblique slots of the said sliding blocks or keys. It will be understood by reference to Fig. 3 that when the blocks or keys K are moved inwardly the oblique slots cause the studs I to be moved outwardly, and thereby draw the bearing-blocks F from the bearing-blocks B. By moving the sliding blocks or keys in the contrary direction the bearing-blocks F will be moved toward the blocks B.

M M designate springs which bear against the outer sides of the blocks or keys K and 55 permit yield of the rolls and boxes.

O designates a roller similar to the roller C, and journaled on the bearing-boxes F. The roller O has preferably at its ends the cams P, which bear against the anti-friction rollers R, which cams and rollers are respectively 60 similar to the cams D and anti-friction rollers E, and which form no part of the invention.

By means of the longitudinally-movable bearing-blocks F and the slide blocks or keys K the bearing-blocks F and, consequently, 65 the roller O, may be moved toward or from the roller C and secured at any desired adjustment in relation thereto.

In order to move the adjusting blocks or keys readily and effect a fine adjustment of 70 the roller, I provide the inclosing-case on its sides with outwardly-extending angle-arms S, which have threaded openings in their outer upturned ends, and provide adjusting-screws T, which work in the said threaded openings 75 and have their inner ends swiveled to the slide blocks or keys. The function of the springs M is to permit the roller O to move outwardly from the roller C in the event that any hard foreign substance should be fed between said rollers with the wheat.

Having described my invention, I claim—
The combination of the case A, the roller C, and the roller O, the movable bearings F for said roller O, provided with the arms G, 85 having the upwardly-projecting studs I, the keepers H, secured to the upper edges of the casing and guiding the arms G, the slide-blocks K, resting transversely in the keepers and provided with oblique slots L to receive 90 the corresponding studs, I, the bearing-brackets S, secured to and standing out from the sides of the casing, the adjusting-screws T, passing through threaded openings in said brackets and having their inner ends swiveled in the outer ends of the blocks K, so that they will move the blocks either inward or outward, and the leaf-springs M, bearing 95 against the keepers and the slide-blocks, substantially as specified.

In testimony that I claim the foregoing as my own I have hereto affixed my signature in presence of two witnesses.

EDWARD T. WILLIAMS.
